UNITED STATES PATENT OFFICE.

CHARLES D. SEEBERGER, OF NEW YORK, N. Y.

CONVEYER.

1,087,893.

Specification of Letters Patent. Patented Feb. 17, 1914.

Application filed January 3, 1911. Serial No. 600,613.

To all whom it may concern:

Be it known that I, CHARLES D. SEEBERGER, a citizen of the United States, residing at New York, in the county of New York 5 and State of New York, have invented certain new and useful Improvements in Conveyers, of which the following is a specification, reference being had therein to the accompanying drawing.

10 This invention relates to conveyers, and especially to that class of conveyers known as traveling stairways extending between different levels and adapted to carry passengers or freight in either direction.

15 The objects of the invention are to provide certain new and useful improvements in the step-frame and wheel-base, and for such purposes the invention consists in the organizations and arrangements of parts herein- 20 after described and particularly pointed out in the claims.

In the accompanying drawings—Figure 1 is an end view of a step unit embodying the features of my present invention and 25 shown associated with a suitable driving chain and tracks; Fig. 2 is a view in elevation taken from the left end of Fig. 1 with part of the riser broken away and with the linkage in section, and Fig. 3 is a top plan 30 view of the parts as shown in Fig. 2.

The conveyer is adapted to travel in upper and lower legs or runs, the former being the transporting run, and each of which is provided with tracks 10 and 11 upon which 35 the step-supporting wheels 12 and 13 run and which are arranged as inner and outer tracks for their respective wheels, the tracks being supported upon a suitable frame work not shown. On the incline the outer tracks 40 are above the inner tracks and at the upper and lower landings the tracks are on the same level, by which arrangement the steps are maintained with their tread surfaces horizontal and in step-like formation on the 45 transporting incline and with their treads in the same horizontal planes at the landings, the change to and from the step-like formation being gradual as the steps pass along the tracks. The tracks at the end of each 50 landing are reversed so that the direction of the travel is reversed from the ascending to the descending run, it being understood of course that the stairway provides for transportation in either direction of travel 55 of the steps and that when the steps are adapted to transport between more than two

levels the tracks are correspondingly extended.

Each step-frame 14 is in the form of a rectangular open body to carry a tread and has 60 downwardly directed portions at one side to carry the associated riser, and is also provided at its ends with downwardly projecting brackets 15 adapted to be bolted to seats on the yokes of the running-gear. The running-gear consists of a step axle 16 whose ends project beyond the step-frame, yokes 17 having oppositely projecting arms 18 and 19, and the front and rear supporting wheels 12 and 13 respectively secured on the arms 65 in the usual manner. The running-gear is wider than the step and the arms 19 are curved or deflected laterally to bring their wheels in a vertical plane outside of or beyond the plane of the other wheels as shown 70 in Figs. 2 and 3. The arms 18 and 19 are rigidly secured to the yokes 17 which are substantially of an inverted U-shape in 75 transverse cross-section, the pendant inner and outer arms 20 and 21 of which provide 80 bearings in which the axle is journaled, and the tops of which are extended inwardly toward the center of the step to form inclined seats 22 for the lower horizontal edges of the brackets 15 which are secured 85 thereto by suitable bolts 23. The inclined seats for the tread are preferably in advance 90 of the center of the tread so that the support for the step is in advance of its center and the load on the step will normally and 95 usually rest in rear of the seats. The span of the yokes affords room for the linkage 100 24 by which the step axles are connected and by which the steps are driven from a suitable driving wheel (not shown), it being understood that any suitable form of linkage may be employed, that here shown being the linkage described and claimed in my application for Letters Patent filed January 3rd, 1911, bearing Serial Number 600,613. The spans of the yokes also afford covers 105 for the joints of the linkage, being located over the axles which form the connecting pivots of the links.

The outer arms of the yokes are extended 110 along the wheel-arms 18, and the yoke is correspondingly long and is set at an angle to the wheel-supporting arms, and the lower portions of the end brackets 15 of the step-frame are correspondingly inclined to fit 115 flush thereupon with the treads of the steps in horizontal position.

The yokes 17 span the linkage and protect its joints and so locate its position with reference to the steps or sections, while affording room for movements of the same at 5 different points of the run, and with the brackets 15 provide convenient means for assembling and disassembling the running-gear and step-frame comprising the step unit.

10 Having described my invention, I claim:—

1. A step-unit comprising a running-gear having an inclined seat, and a step-frame bolted to the seat.

15 2. A step-unit comprising a running-gear having opposite yokes provided with inclined seat-portions, and a step-frame having inclined end-brackets bolted to the seat portions.

20 3. A step-unit comprising a running-gear having an axle and opposite yokes provided with inclined seats and with oppositely extending wheel-arms, and a step-frame having inclined end-brackets bolted to the seats.

25 4. In a device of the class described, tracks, steps each having a running-gear provided with supports coöperating with said tracks, a system of links connecting said gears, yokes on the gears spanning the links, 30 and a step-frame bolted to the yokes.

5. In a device of the class described, tracks, steps each having a running-gear provided with supports coöperating with said tracks, a system of links connecting said steps and located at their ends, a yoke on 35 each side of the step spanning the links, inclined seats on the yokes, and a step-frame having brackets provided with inclined faces bolted to the seats.

6. In a moving-stairway, tracks, connected step units having wheels at each end to travel over the tracks, each step-unit comprising a running-gear having end yokes spanning the connections between the units and providing inclined seats, and a step- 45 frame having inclined end-brackets secured to said seats.

7. A step for moving stairways, having a suitable tread, a yoke at each end of the step having supporting-wheels and an inclined seat for the tread in advance of the center thereof, and linkage pivoted within the yoke.

In testimony whereof I affix my signature in presence of two witnesses.

CHARLES D. SEEBERGER.
